(57) **CLAIM**

The ornamental design for a rectangular drawer organizer design, as shown and described.

DESCRIPTION

FIG. 1 is a perspective view of a rectangular drawer organizer in accordance with a first embodiment of my design; showing the drawer organizer with equal length and width dimensions;

FIG. 2 is a front elevational view of the drawer organizer shown in FIG. 1, with the rear elevational view and both side elevational views being identical;

FIG. 3 is a bottom plan view of the drawer organizer shown in FIGS. 1 and 2;

FIG. 4 is a top plan view of the drawer organizer shown in FIGS. 1-3;

FIG. 5 is a perspective view of the drawer organizer in accordance with a second embodiment of my design and with length and width dimensions being unequal;

FIG. 6 is a top plan view of the drawer organizer shown in FIG. 5;

FIG. 7 is a bottom plan view of the drawer organizer shown in FIGS. 5 and 6;

FIG. 8 is a left side elevational view of the drawer organizer shown in FIG. 5, with the right side elevational view being identical; and,

FIG. 9 is a front elevational view of the drawer organizer shown in FIG. 5, with the rear elevational view thereof being identical.
